UNITED STATES PATENT OFFICE.

HARVEY TILDEN AND FREDERICK S. GUERBER, OF HARRISBURG, PA.

RAILWAY-SWITCH AND SIGNAL APPARATUS.

SPECIFICATION forming part of Letters Patent No. 237,787, dated February 15, 1881.

Application filed November 5, 1880. (No model.)

To all whom it may concern:

Be it known that we, HARVEY TILDEN and FREDERICK S. GUERBER, of Harrisburg, county of Dauphin, State of Pennsylvania, 5 have invented or discovered a new and useful Improvement in Railway-Switches and Signal Apparatus; and we do hereby declare the following to be a full, clear, concise, and exact description thereof, reference being had to the 10 accompanying drawings, making a part of this specification, in which—like letters indicating like parts—

Figure 1, Sheet 1, is as diagram or plan view of a system of signals and switches such as 15 may be supposed, for purposes of illustration, to exist or be arranged at a way-station of a double-track road, and illustrating in outline the manner of applying our present improvements thereto, the lower section of said figure 20 from the line *b b* being a continuation of the upper section from the line *a a*, and a portion of tracks and connections in both sections being broken away. Fig. 2, Sheet 2, and Fig. 2^a, Sheet 3, represent conjointly, when united 25 on the line *c c* of Fig. 2 and the line *d d* of Fig. 2^a, a plan view to an enlarged scale of portions of the tracks and apparatus employed. Fig. 3, Sheet 4, is a detached view to a still larger 30 scale of a switch and signal operating mechanism. Fig. 4 is a sectional elevation to an enlarged scale of the cabin from which the signals are moved, and showing the apparatus therein employed; and Fig. 5 is a cross-section thereof in the plane of the line *x x*, Fig. 4.

35 Our present invention relates to apparatus primarily designed for use at way-stations on the line of a double-track road where one or more sidings are required.

One of the most frequent causes of railway 40 accidents arises at switches of way-stations, sometimes from errors of the switchman in setting the switch to the siding when the main track ought to be open, so that when a through-train approaches it runs off onto the siding 45 and often in collision with cars on the siding. It is also a favorite expedient with malicious persons to throw a switch to the siding for the purpose of causing such an accident, or, what is sometimes equally disastrous, the switch is 50 partly shifted, so as to derail the train. This last is an especially serious element of danger,

since sometimes the switch can be moved far enough for the purpose thus indicated without so far shifting the switch lights or signals as to give notice even to the most cautious 55 engineer; also, it sometimes happens that, when a train takes the siding in order to allow a through-train to pass, the tail of the train is not run entirely onto the siding so as to leave the main track clear, and a collision results. 60

Our apparatus is designed to prevent the occurrence of accidents of this class, and it is so organized that the signal can be given for "main line clear" only when the switch is set 65 for the main-line track, and in case the switch is either intentionally or through error or malice set to the siding, or so far set over toward the siding as to break the main-track connection, such movement of the switch will necessarily 70 result in the setting of the signal or signals at "danger." Hence, if the engineer of a through-train, on approaching a station, finds the signal set at "safety" he knows the switch is properly set; but if he finds the signal at "danger" he 75 knows something is wrong with the switch, or else that he is flagged, and he is then bound to proceed with due caution or stop, as the case may be.

Referring to Fig. 1, A may represent a cabin at any convenient point, and preferably at or near the station-house.

B is the right-hand through-track, and B' the other, the arrows indicating the directions of the movements of trains. The right-hand 85 track is guarded by a signal at *s* and the left-hand track by a signal at *s'*, such signals being of any suitable construction and arranged at any desired distance beyond the switch or switches against which protection is desired. 90 As an illustration, on this diagram the switches on the right-hand track which are to be protected are three in number, *a a' a²*, and for this purpose a hydraulic pipe, *c*, (represented by dotted lines,) extends from the cabin A to 95 the switch *a²* farthest from the signal through an apparatus, here marked D, then back to the next switch, *a'*, through a like apparatus, then to the switch *a*, as before, and thence to the signal. The left-hand track has also three 100 switches, *e e' e²*, and a pipe, *c'*, runs, as before, through apparatus D, as before, first to switch

e, then to *e'*, then to *e''*, and finally to the signals *s'*. The cabin-pipe connections and apparatus therein will presently be explained.

For the purposes of the part of our invention now under consideration it will be sufficient if the pipes *e* *e'* be charged with water or other suitable liquid under sufficient pressure, and that such pressure be capable of being turned on or let off at pleasure by the operator or station-master, who ordinarily will have in the cabin A a pair of levers for such purpose.

In Figs. 2 2^a we have shown to an enlarged scale the signals *s*, switches *a* *a'*, and the apparatus D D appertaining thereto, and in Fig. 3, Sheet 4, we have still further enlarged the apparatus.

Referring now to Fig. 3, last named, *c* is the pipe leading from the cabin and on in the line of connection, as specified. At this point, however, it enters a cylinder, *d*, on one side, and leaves on the other about midway of the length of the cylinder. In this cylinder we arrange a long piston, *d'*, which in its normal position nearly fills the bore of the cylinder, and we make a hole diametrically through it, as shown, and so that, the piston being in its normal position, such hole shall be in line with the ports in the cylinder with which the ends of the pipe *c* are connected, such hole forming, in fact, a part or section of the pipe; but the piston and cylinder are so constructed and proportioned that if the piston is drawn out at all the hole through it will be brought out of line with the ends of the pipe *c*, and the solid body of the piston will close both pipe ends. The extreme end of the cylinder has a pipe-connection, *c'*, with the pipe *c*, as shown.

In describing this part of our invention we assume that a hand-lever is employed to throw the switches. Such a lever is shown at *b'* on the switch-stand *b*. From the lower end of this lever a rod, *b''*, extends to and connects with a plate, *g*, which slides back and forth in suitable guides or ways on the foundation *g'*. The plate *g* is slotted on its under side, as at *i* *i'* *i''*, (dotted lines), and in such slots we arrange a pair of wrists, one of which is connected to the stem *d''* of the piston *d'*, and the other to a connecting-rod, *f*, which at its other end is pivoted to a bell-crank, *f'*, and the latter at its other end is pivoted to the switch-bridle *f''*.

Assuming, now, that the pipe *c* is full of water under pressure, and that all the apparatus D on the line of pipe *c* are in their normal position, so that water-pressure may act through the perforated cylinders and pistons, it will be seen, Figs. 2 and 2^a, that the main track B will be unbroken, and by water-pressure the signal at *s* will be held up at "safety." This indicates correctly to the engineer of an approaching through-train that everything is clear, and that he can go ahead; but in case any motion whatever is imparted to the switch-lever *b'* with reference to setting the movable switch-rails to or toward the siding, intention-

ally or maliciously, the first effect on the apparatus D is to move the sliding plate *g*, and by moving that to cause the wrist on the end 70 of *d''* to slide down the incline *i'*. This at once shifts the piston *d'* so as to cut off both adjacent ends of the pipe *c*. Water from the cabin or back can then have no effect whatever, but water from the counterweighted signal, or forward, pressing back, passes by the pipe *c'* into the space made vacant in the cylinder *d* by the partial withdrawal of the piston *d'*, and the capacity or size of this cylinder end is such that by the time the wrist on *d''* has reached 80 the opposite end of the incline enough of the water in the pipe *c* forward toward the signal will have flowed through *c'* into the cylinder *d* to allow the signal to come down to "danger;" and this effect will follow even if 85 there be little or no back-pressure, since the piston *d'*, in going out, acts somewhat as a suction-pump, to draw the water through *c'* into *d*, and so lower the signal to "danger;" but it will be observed that, while the signal has 90 thus been brought to "danger," the movable switch-rails have not yet begun to move at all, since while the wrist on the end of *d''* has been traveling down the incline *i'* the wrist on the end of *f* has simply slid along the slot *i*, 95 without imparting to *f* any motion whatever. Hence it is a necessity of the construction described that any shifting movement of the rails from the main track to the siding must be preceded by the shifting of the signal to 100 "danger," and the engineer of a through-train, on finding the signal at "danger," will know that the switch is wrong, and he will act accordingly.

It will also be observed that each of the apparatus D is complete in itself; that when in a normal position hydraulic pressure acts forward through all to keep the signal at "safety," and that such a displacement or movement of any of them as results in a movement of the rails will bring the signal to "danger." Hence, if all the switches of one track have their apparatus D on a pipe-line, *c*, leading from the operating-valve at the cabin to the signal, the misplacement of any one of the apparatus D 115 lowers the signal to "danger" and warns the engineer. The same facts are true of all the switches on the other track and pipe, so that separate explanation of them is not necessary.

It will also be obvious from Fig. 3 that, if the switch be misplaced and the signal brought to "danger," the restoration of the switch-connection to the main-track line will, by the reversal of the motions described, result in forcing the piston *d'* back into the cylinder *d*, which 125 motion will, on the force-pump principle, drive the water out of the cylinder *d* through the pipe *c'* to the signal-cylinder, where it will cause the signal to be restored to a "safety" position; or if there be any loss in the amount or bulk 130 of water the deficiency will be supplied through the hole in the piston, which will again be brought into line with the pipe ends of *c*.

When it is desired to set the switch to the

siding the hand-lever b' will be shifted till the wrist on the end of d^2 occupies the extreme end of the slot i^2 and the wrist on f has passed down the incline i' and occupies a position at 5 the contiguous end of i^2 .

We do not in our present application limit ourselves to any particular way of moving the valve or valves by which, at the cabin A, the hydrostatic pressure is turned on or off; nor 10 are we particular as to the construction of valve employed, provided it be suitable for the purpose. One suitable form of valve is shown in Patent No. 229,341, granted to us June 29, 1880. In our preferred arrangement of apparatus 15 we arrange such a valve in each of the pipe-lines $c c'$, as illustrated at n in Figs. 4 and 5, where we have shown, to an enlarged scale, so much of a hand apparatus as is necessary to show how the apparatus may be used at way- 20 stations.

T is a tank arranged at convenient height for receiving the waste without emptying the pipes $c c'$ when it is desired to operate the signals without moving the switches. This tank 25 may be supplied with water from the cabin-roof, or by a common hand or force pump, or in other convenient way. A pipe, t , leads from it through a check-valve, v , to an accumulator, V, the plunger V' of which is loaded 30 with a weight, W, such as will by its gravity maintain the desired hydrostatic pressures in the pipes $c c'$ for moving and holding the signals at "safety." The pressure is transmitted from the accumulator, by pipe t' , to the valve 35 n ; and in order that both valves may be supplied from one pipe we introduce a common tank supply-pipe, P, with a connection thence to each valve n . From the valve n the pipe c leads through the apparatus D to the signal, 40 as already described. The waste-port of each valve has connection with a tank waste-pipe, P' , and a pipe, t'' , leads from the latter to the tank T. Each valve n is operated by any suitable means, one such being a bent lever, n' , 45 and stem n^2 .

While for most purposes we do not desire to employ interlocking devices in connection with our present apparatus, such devices may be usefully employed in some cases, and hence 50 we do not exclude them.

In order to enable the accumulator to be charged at way-stations where mechanical power is not available, we provide a hand-pulley, R R'; for the purpose, which pulley is to 55 be fitted up and proportioned with reference to the power available. If the weight is heavy and a single man is expected to raise it, then the pulley-rope should be passed back and forth over two or more sheaves, or a differential pulley of any known form or construction may be employed. As the weight W and with it the plunger V' are thus raised, water from the tank T will flow into the accumulator through the check-valve v , and its back-flow will be 65 prevented by the seating of the same valve.

It is one of the important features of our present apparatus that the switchman can

work his hand-switches the same as if the hydraulic apparatus were not present at all, and while doing so he has the benefit of an 70 automatically - operated system of signals. When he is engaged in switching from, to, or across the main track, his signal is necessarily at "danger," so as to stop all approaching trains, and as soon as his main track is clear, 75 by resetting his switches properly, the proper signal comes to "safety," and for these purposes his presence in the cabin is not required.

Ordinarily the valves n will be in position 80 for water-pressure to act from the accumulator to the signal, and the only occasion for reversing the valve n will be when the station-master or operator at the cabin desires to flag a train, which he may do by letting off the pressure, and so bringing down the signal to 85 "danger."

Instead of allowing the water to flow from c through c^2 into the cylinder d for the purpose of shifting the signal to "danger," it will be feasible to open a valve or port by the piston-motion, and allow enough water to effect the shifting of the signal to flow into a separate chamber or raised waste-tank, such as is used in the cabin A, Fig. 4, or even to escape, suitable means being added, as by a weighted valve 95 or vertical waste-pipe of proper height, to prevent the escape of more than the necessary amount of water for the purpose. Also, other suitable wrist and guide connections may be made at or near the lower end of the switch-shifting lever by which to break and make the 100 hydraulic column through the pipe c , provided the function and operation remain substantially unimpaired.

For a single-track road a single set of the 105 same apparatus may be employed, the same as herein described from one of the double tracks, but the signal should then be put at such point that it will be readily seen from both directions, and the pipe c , after passing the 110 last switch in the series, should then go to the signal; or, after so passing the last switch in the series, the pipe c may be divided and one branch go to one signal in one direction and the other to another signal in the other direction. Then on the shifting or misplacement of any switch in the series both signals 115 will come to "danger."

In the working of the apparatus described, proper order should be followed in setting 120 and resetting of switches, to the end that at no time or place should an undue or a breaking strain be brought on the pipes containing a water-column.

We claim herein as our invention— 125

1. In combination with a hydraulic pipe, c , extending from a head or source of pressure to a signal, an interposed perforated cylinder and piston, the piston being connected with the switch movement, and a pipe, c^2 , leading 130 from the end of the cylinder to the pipe c at a point forward or toward the signal, substantially as set forth.

2. In combination with a hydraulic pipe ex-

tending from a head or source of pressure to a railway-signal and past one or more switches, a switch-shifting apparatus which shall break the hydraulic column at or near such switch and make or open a chamber or escape from the pipe leading thence to the signal, sufficient in capacity to secure the automatic shifting of the signal to "danger" position, substantially as set forth.

10 3. In an apparatus wherein the signal operated by hydraulic pressure is arranged to protect a series of two or more switches in the same track, the combination of a switch-shifting mechanism at each switch, an apparatus for

15 breaking the hydraulic column and opening a chamber or escape, and a connection from each switch-shifting mechanism to said apparatus, substantially as set forth, whereby the misplacement or shifting of any one of such

20 switches from its normal position shall cause the shifting of the signal to a "danger" position.

4. In combination with pipes c^2 , signal s , cylinder d , and piston d' , the plate g , and switch-connection f , substantially as set forth.

25

5. In a hydraulic apparatus having an elevated tank or head, the combination of an accumulator, a connecting-pipe, t ; and check-valve v , a pipe, t' , leading from the accumulator to valve u , a pipe, c , leading thence to the signal, and a pulley apparatus constructed and operated substantially as and for the purpose set forth.

In testimony whereof we have hereunto set our hands.
